ELECTRICAL WARP STOP MOTION

Application filed July 9, 1930. Serial No. 466,623.

This invention relates to improvements in electrical warp stop motions and it is the general object of the invention to permit the use of a warp stop motion formed of a plurality of assembled similar units wherein each unit supports a contact bar and also carries an energized contact for the live electrode of the bar.

In a form of warp stop motion which has gone into use there are employed contact bars which are held in position by spacing or holding units mounted on a threaded bar. There are as many units as the requirements of the warp demand and when it is desired to enlarge the motion more units may be added. It is a further object of my invention to provide each of these spacers or supporting members with a pair of contact springs, one of which engages a live electrode of the contact bar supported by the spacer and the other of which extends to the adjacent unit so that a circuit is established through all of the units.

Each group of elements includes a spacer, two electrodes and a pair of springs, the spacer having a pocket or recess to receive the contact bar which is so formed as to permit entry of the bar without objectionable deformation of the contact spring.

With these and other objects in view which will appear as the description proceeds, my invention resides in the combination and arrangement of parts hereinafter described and set forth in the claims.

In the accompanying drawings, wherein a convenient embodiment of my invention is set forth.

Fig. 1 is a vertical transverse section through a warp stop motion made according to my invention,

Fig. 2 is a vertical section on line 2—2 of Fig. 1.

Fig. 3 shows two units in spaced relation before being assembled, and

Fig. 4 is a vertical section on line 4—4 of Fig. 2 showing the manner of supporting and insulating the contacts from the spacing units.

As shown in Figs. 1 and 2, I provide a threaded rod 10 which may extend parallel

to the warp W and have a pair of clamping nuts 11 and 12 between which are located a plurality of substantially similar spacing units 13 and an end member 14. Each of the units 13 is provided with a pocket or recess 15 having a lower supporting surface 16 on which rests a contact bar designated generally at 17. The bar has an outer inclosing electrode 18 which may be grounded through the spacing units and rod 10 and said bar also has an inner live electrode 19 insulated from the other electrode. A rib 20 runs longitudinally along the grounded electrode and cooperates with a drop wire D which when fallen due to warp fault is effective to electrically contact the live and grounded electrodes of the corresponding bar and thus effect stoppage of a loom or other machine to which the motion may be applied. The nuts 11 and 12 clamp the spacing units together so that they form in effect a unitary structure mounted on the bar 10.

The matter thus far described may be substantially the same as set forth in co-pending application Ser. No. 462,651 filed by Payne.

Each of the units 13, and also the end member 14, is provided with a lateral extension 30 having a bore 31 in which is located an insulating bushing 32. A bolt 33 of current conducting material extends through the bushing and is electrically insulated from the extension 30 by means of upper and lower insulating washers 34 and 35, respectively. Between the bolt head 36 and the washer 34 lie the feet of two contact springs one of which extends upwardly as at 37 and the other of which projects horizontally as at 38. A nut 39 on the bottom part of the bolt holds the springs in position with respect to the corresponding spacer or unit.

The upwardly projecting spring 37 has a rounded portion 40 which is adapted for engagement with the live electrode 19. The rounded portion does not extend to the top of the notch but preferably engages the live electrode intermediate its top and bottom, and if desired opposite the rib 20. The reason for this construction is to permit a sufficient opening between the spring contact

- and the top 41 of the unit which defines the upper end of the notch 15 to permit ready entry of the contact bar. The horizontal spring 38 extends to the head of the bolt on 5 the adjacent unit so that the contacts of all of said units are electrically connected. The lead-in wire 42 may be connected to any of the bolts, but as shown herein is held to the bolt carried by the end member.
- 10 By the construction set forth herein each of the units 13 has associated therewith live and grounded electrodes together with a pair of contacts all of which form a group of elements movable as a whole to position on the 15 rod 10. The contact bar is positioned with respect to its corresponding spacer 13 as is also the spring 37, so that there is very little if any variation in the relation of these two parts and even though adjacent spacers be 20 separated by different amounts there will still be proper contact between each live electrode and its spring.

From the foregoing it will be seen that I have provided a simple means for electrically 25 connecting the live electrodes of contact bars of a warp stop motion built up on the unit principle wherein any desired number of groups of elements may be employed, and that each group has a spacer which determines 30 the position of its corresponding live electrode and a spring 37 carried thereby.

Having thus described my invention it will be seen that changes and modifications may 35 be made therein by those skilled in the art without departing from the spirit and scope of the invention and I do not wish to be limited to the details herein disclosed, but what I claim is:

1. In an electrical warp stop motion, a 40 plurality of groups of elements, each group containing an electrode to be energized, a separate supporting spacing unit to hold the electrode, and a contact device to engage the electrode, said contact device being supported 45 by the same spacing unit which supports the electrode in contact therewith, each supporting unit being removable independently of the other units.
2. In an electrical warp stop motion, a 50 plurality of similar groups of elements held adjacent each other to form a substantially unitary structure, each group including a spacer having a pocket, a contact bar located in the pocket and having a live electrode, and a contact spring on the spacer and having engagement with the live electrode in the pocket.
- 55 3. In an electrical warp stop motion, a 60 plurality of similar groups of elements held adjacent each other to form a substantially unitary structure, each group including a spacer, a contact bar having a live electrode supported by the spacer and lying between two adjacent spacers, and an electric contact spring device carried by each spacer and

normally held in contacting relation with the live electrode supported by said spacer.

4. In an electrical warp stop motion, a plurality of groups of elements held adjacent each other to form a substantially unitary 70 structure, each group having an insulated live electrode and a contact spring device, and each group further having a common support for the live electrode and contact device engaging the same.

5. In an electrical warp stop motion, a plurality of groups of elements held adjacent each other to form a substantially unitary structure, each group including a supporting unit, a live electrode mounted on the 80 supporting unit to have engagement with a drop wire, and a contact spring for the electrode, said electrode and spring being insulated from the supporting unit and being movable with the latter without relative motion with respect thereto.

6. In an electrical warp stop motion, a plurality of similar groups of elements held adjacent each other to form a substantially unitary structure, a contact bar having a live 90 electrode, a spring to have direct contact with the live electrode, and a supporting and spacing unit for the bar and spring, said bar and spring being mounted on and movable with the unit without movement relative to each other or with respect to the unit.

In testimony whereof I have hereunto affixed my signature.

CLARENCE R. KRONOFF.
